UNITED STATES PATENT OFFICE.

WILLIAM H. WALTER, OF CHICAGO, ILLINOIS, ASSIGNOR TO FRANK G. KAMMERER, OF CHICAGO, ILLINOIS.

RINSING DEVICE.

SPECIFICATION forming part of Letters Patent No. 763,647, dated June 28, 1904.

Application filed May 14, 1903. Serial No. 157,043. (No model.)

To all whom it may concern:

Be it known that I, WILLIAM H. WALTER, of Chicago, in the county of Cook and State of Illinois, have invented certain new and useful 5 Improvements in Rinsing Devices; and I do hereby declare that the following is a full, clear, and exact description thereof, reference being had to the accompanying drawings, and to the letters of reference marked thereon, 10 which form a part of this specification.

This invention relates to improvements in devices for rinsing tumblers and like articles, the same being more especially adapted for use in connection with liquid dispensing or 15 vending apparatus, soda-fountains, and the like, while being capable of use for other purposes.

The invention consists in the matters hereinafter described, and pointed out in the ap- 20 pended claims.

In the accompanying drawings, illustrating my invention, Figure 1 is a view in central vertical section of an apparatus or device embodying my invention. Fig. 2 is a plan section thereof, taken upon the line 2 2 of Fig. 1. Fig. 3 is a detail section taken through the water-delivery devices of the apparatus, showing a changed position of the parts illustrated in Fig. 1. Fig. 4 is a detail section, on an en- 30 larged scale, showing the valve-seat illustrated in Fig. 1.

As shown in said drawings, A indicates a vertical water-delivery pipe, the upper end of which constitutes the discharge-nozzle of the rinsing device and which has vertically-sliding 35 movement in an upright tube or valve-casing B, which is rigidly attached at its lower end to a water-supply pipe C.

D indicates a tumbler-support, which sur- 40 rounds the pipe A and tube B and is attached to and moves vertically with the pipe A. The tumbler-support is surrounded by an annular wall E, which forms with the tumbler-support an annular recess F to receive the edge or 45 lower margin of a tumbler, such as is indicated at G, when the same is placed in an inverted position over the upper end of the pipe A. The tumbler-support D consists of an inner cylindric wall D' and a horizontal flange

D² on the lower edge of said wall D', which 50 flange extends outwardly nearly to the wall E and forms the bottom of the annular recess F. The cylindric part D' of the tumbler-support is attached to the pipe A at a point near its upper end by means of an inwardly-deflected 55 part D³, preferably made of dome shape. The flange D² constitutes a rest or support for the tumbler, which is placed over the water-supply pipe A, the lower edge of the inverted tumbler resting upon the top of the said flange D², 60 as shown in Fig. 1.

H indicates a circular horizontal plate which is attached at its margin to the wall E and forms with the latter a circular water-recep- 65 tacle, which surrounds the casing B and pipe A and in which the tumbler-support is located. The said outer wall E is shown as supported from or upon the casing B by means of the plate H, which has a central aperture for the passage of said casing B and is secured to said 70 casing. At its outer edge the said plate H is shown as provided with a depending annular flange, which fits within the annular wall E and may be secured thereto by bolts h, as shown, or in any other suitable manner. The 75 annular wall E and the cylindric wall D' of the tumbler-support form the inner and outer walls of the annular recess F, said inner and outer walls serving to aid in holding the glass or tumbler in place on or over the delivery- 80 pipe A. The receptacle formed by the wall E and plate H serves to hold water, which aids in the rinsing of the edge of the glass, as will hereinafter more fully be set forth.

Beneath the several parts described is lo- 85 cated a drainage cup or receptacle I, adapt- 90 ed to receive water escaping from the upper part of the apparatus and to conduct the same to a drainage-pipe J. The said drain- age-pipe J is shown as connected centrally 95 with the cup I at a point beneath the pipe A. The supply-pipe C is shown as having the form of a fitting provided with a double bend, which brings its vertical lower part or stem c at one side of the drainage-pipe J. A tight 95 joint is formed between the vertical part c of the fitting C and the cup I, consisting of a flange c' above the said cup, a ring c² below

the cup, and a nut c^3 , which bears against the ring, which has screw-threaded engagement with the said part c and bears against the ring, packing-rings c^4 c^5 being interposed between 5 said shoulder and ring and the cup.

The lower margins of the outer wall E are shown as extended downwardly past the plate H to the bottom of the cup I, so that the said wall E rests upon and is partially supported 10 by the marginal part of said cup I. Small drainage-openings i are shown as formed in the lower margin of the wall E, so as to permit the water which may flow over the wall E and which falls into the outer part of the 15 cup I outside of the said wall E to reach the inner part of said cup and the drainage-pipe J.

Now referring to the devices illustrated for controlling the flow of water from the upright delivery-pipe A, devices are provided as follows: The lower parts of the stationary tube or valve-casing B and the delivery-pipe A constitute a valve by which the flow of water to the delivery-pipe from the supply-pipe is controlled and which is operated through the vertical movement of the delivery-pipe in said 20 casing. Said casing B is provided in its lower part with a cylindric interior bearing-surface or seat b , within which the cylindric lower part of the pipe A fits and slides, and said 25 casing B is provided at its lower end with an annular downwardly-facing valve-seat b' , against which is adapted to bear a valve-disk A', which is attached to the lower end of the pipe A. The said pipe A is held normally at 30 the upward limit of its movement and with the valve-disk A' in contact with the valve-seat b' by means of a spirally-coiled spring K, interposed between a shoulder on the pipe A and an opposing shoulder in the casing B. As 35 herein shown, the upper part of said casing B is enlarged to receive the spring K, and said spring bears at its lower end upon an upwardly-facing interior shoulder b^2 in the casing and bears upwardly at its upper end 40 against a shoulder formed by means of a flange a on the pipe A. To limit the downward movement of said pipe A and the attached tumbler-support, the said casing B is provided with an interior upwardly-facing shoulder b^3 , located 45 at the upper end of the bearing-surface b and below the shoulder b^2 , while the pipe A is provided with a downwardly-facing shoulder formed by means of a second annular flange a' , which is arranged upon the pipe in position 50 for contact with the shoulder b^3 when the pipe is at the lowermost limit of its movement. A packing-ring b^4 is preferably applied to the shoulder b^3 , so as to prevent the upward escape of water between the casing B and the 55 pipe A when the said pipe is in its depressed or lowermost position. The bore or passage of the said pipe A is closed at its lower end excepting for ports or passages a^2 , which extend radially from the said bore to the outer 60 face of the pipe, these ports a^2 being so ar-

ranged that when the pipe is in its depressed position they will be brought below the interior bearing-surface b , and thus afford free ingress of water from the supply-pipe C to the said pipe A. Said ports a^2 are, moreover, located above the lower end of the pipe A, so that when said pipe is thrown to the upward limit of its movement by the action of the spring K the ports will be closed by the surrounding bearing-surface of the casing B and access of water thereby prevented. The valve-disk A' by its contact with the downwardly-facing valve-seat b' at the time the pipe A is at the upward limit of its movement serves to prevent any leakage of water 80 between the lower end of the pipe A and its seat within the casing B.

At its upper end the water-supply pipe A is provided with a plurality of jet-openings 85 through which water is ejected from the pipe against the inner surface of the bottom and sides of the tumbler.

The spring K is made of such stiffness or strength that it will hold the valve closed under the weight of a tumbler resting on the 90 flange D² of the tumbler-support, so that when the tumbler is merely resting on the device there will be no flow of water through the same; but if the hand is pressed downwardly upon the tumbler the said spring will be compressed and the valve formed by the pipe A and the surrounding casing B will be opened 95 and will permit a supply of water to be delivered to the pipe for the purpose of rinsing the tumbler.

As a means of insuring the rinsing of the lower edge or margin of the tumbler by the water which flows from the supply-pipe A, I provide a construction as follows: In the plate H is formed an escape orifice or port L, and attached to the said plate around the said port is a packing-ring or gasket M, which rises above the plate and is adapted for contact with the bottom surface of the flange D². The parts are so arranged that when the water-supply pipe A and the tumbler-support are depressed by pressing down upon the tumbler the bottom surface of the flange D² will press downwardly on the ring M, so as to close the opening or port L, and thus prevent the passage of water therethrough so long as the parts named are held depressed by downward pressure on the tumbler. When, however, pressure on the tumbler is released and the same, with the tumbler-support, rises under the action of the spring K, then the port L will be opened and the water previously confined above in the receptacle formed by the wall E and plate H is allowed to escape and flow into the drainage-cup.

A special advantage is gained by the ring or gasket M, arranged to rise above the top surface of the plate H in position for contact therewith of the flat bottom of the flange D², for the reason that when the parts are thus 130

- arranged any part of the flange D² will press on the said ring M when the tumbler-support is depressed, and it is unnecessary to provide any device or means to keep the tumbler-support from turning in the device shown in the drawings. Said tumbler-support is left entirely free to turn by rotation of the pipe A in the valve-casing, and such turning of the tumbler-support has no effect on the action of the valve which is formed by the port L and flange D². I have also shown a cushion-block N as attached to the plate H at a point diametrically opposite the port L, so that it will arrest the downward movement of that side of the flange D² when the flange D² comes in contact with the gasket M, so that the downward pressure on the tumbler will have no tendency to tip or tilt the tumbler-support and throw the pipe A out of its vertical position.
- It will be manifest from the above that when pressure is applied to the tumbler, so as to depress the tumbler-support, water discharged from the pipe A will rise within the wall E around the lower edge of the tumbler, so as to wash or rinse the same, and when the pressure on the tumbler is released the tumbler-support will rise and the water will be drained from the receptacle. If the tumbler be held depressed so long that the recess F becomes filled, the surplus water may be allowed to overflow over the upper edge of the outer wall E into the outer part of the cup I.
- As a further improvement I provide an overflow-pipe O, which is arranged vertically within the central elevated part of the tumbler-support and is attached at its lower end to the plate H, the overflow-pipe being open at its upper and lower ends and terminating at its upper end somewhat below the level of the top edge of the outer wall E. When such overflow-pipe is employed, if a sufficient quantity of water enters the receptacle to nearly fill the same the water will overflow through the pipe O, and thus prevent the same from rising above a desired level.
- Connecting holes or apertures d are found in the inner part or wall D' of the tumbler-support, so as to establish free connection between the interior of the tumbler-support and the annular recess F, and thus permits the water to drain from the space between the lower edge of the tumbler and the inner part of the tumbler-support. These holes d also serve to prevent the formation of a partial vacuum within the tumbler as the same is lifted, and thus prevents liability of water which has accumulated within the tumbler being lifted with the same in case the tumbler be removed from its place while the receptacle still contains a considerable quantity of water.

I claim as my invention—

1. A device for the purpose set forth comprising an upright, vertically-movable deliv-

ery-pipe, means by which water is admitted to the delivery-pipe when the same is in its depressed position, an annular tumbler-support connected and movable with the said pipe, a lifting-spring which acts to lift the pipe and tumbler-support, and a receptacle surrounding the said tumbler-support, said receptacle being provided in its bottom with a valved opening which is opened and closed by the movement of said tumbler-support.

2. A device for the purpose set forth comprising an upright delivery-pipe, said pipe being vertically movable and provided with means by which water is admitted to the same when in its depressed position, an annular tumbler-support connected and movable with the said pipe, a lifting-spring which acts to lift the pipe and tumbler-support, and a receptacle surrounding the said tumbler-support, said receptacle being provided in its bottom with a valved opening which is opened and closed by the movement of the said tumbler-support and said receptacle being also provided with an overflow-pipe opening through the bottom thereof.

3. A device for the purpose set forth comprising water-supplying means, a vertically-movable tumbler-support, a lifting-spring which acts to lift the tumbler-support, a receptacle which surrounds said tumbler-support, provided with an outlet in its bottom, and means operated by the movement of said tumbler-support for opening and closing said outlet.

4. A device for the purpose set forth comprising water-supplying means, a vertically-movable tumbler-support, a lifting-spring acting to lift said tumbler-support, a receptacle which surrounds the tumbler-support and is provided with an outlet and with a gasket surrounding said outlet; said tumbler-support being provided with an annular surface adapted for contact with said gasket to close said outlet when the tumbler-support is depressed.

5. A device for the purpose set forth, comprising an upright water-delivery pipe, a vertically-movable tumbler-support, means operated by the movement of the tumbler-support for cutting off the supply of water from and admitting water to said delivery-pipe, a lifting-spring acting to lift the tumbler-support, a receptacle surrounding the tumbler-support, and provided with an outlet in its bottom, and means operated by the vertical movement of the tumbler-support for opening and closing said outlet.

6. A device for the purpose set forth, comprising water-supplying means, a vertically-movable tumbler-support provided with a central elevated part and a horizontal flange adapted to form a support for the lower edge of an inverted tumbler, a receptacle surrounding the tumbler-support and provided with an outlet in its bottom and a gasket surrounding

said outlet and adapted for contact therewith of the horizontal flange of the tumbler - support.

7. A device for the purpose set forth, comprising an upright, vertically-movable delivery-pipe, means operated by the movement of said pipe for admitting water to and cutting it off from said pipe, a tumbler-support attached to the pipe and provided with an annular, horizontal flange, adapted to form a support for the edge of an inverted tumbler, a lifting-spring acting to lift the tumbler - support, a receptacle surrounding said tumbler-support

and provided with an outlet in its bottom and a gasket surrounding said outlet and adapted for contact therewith of the bottom surface of said flange when the tumbler - support is depressed.

In testimony that I claim the foregoing as my invention I affix my signature, in presence of two witnesses, this 12th day of May, A. D. 1903.

WILLIAM H. WALTER.
